UNITED STATES PATENT OFFICE.

ROBERT OLIVER GEARY, OF ROCKDALE, AUSTRALIA.

LEVER-TOP CAN.

Application filed January 29, 1924, Serial No. 689,289, and in Australia February 17, 1923.

In a lever-top can, the top or can fits in what is termed the collar which is a piece of metal of annular form having on its internal periphery a flange, and being secured 5 at its outer periphery to the edge of the body of the can.

As hitherto constructed the collar is not of sufficient strength and rigidity and is apt to be depressed or distorted and the flange 10 thereof split by the action of the forcing into position of the top or cap, resulting in a defective joint which is neither air-tight nor fluid-tight and may permit the escape of the contents of the can.

15 The object of this invention is to provide a can of which the collar is so strengthened as to be capable of maintaining its form against the pressure required to force home the top or can.

20 With this object my improvements consist in the provision of corrugations or equivalent deformations in the collar of the can, so arranged and disposed that the collar, instead of being a plain annulus, is 25 ribbed or bulged at intervals and thus strengthened against flexure.

Two alternative embodiments of my invention are illustrated in the accompanying drawings to which I will now refer.

30 Fig. 1 is a part perspective view of a lever top can (with top) embodying one form of my improvements, i. e. spaced radial corrugations.

Fig. 2 a fragmentary perspective (partly 35 in section) of the collar;

Fig. 3 a part sectional elevation to a larger scale of the upper part of the can taken through one of the corrugations;

Fig. 4 is a similar view to Fig. 2 but 40 showing a modification in the shape of the collar strengthening means, i. e. spaced bulges.

Fig. 5 is a part sectional elevation to a 45 larger scale of the construction shown in Fig. 4, taken through one of the bulges.

A is the can body, B the top or cap and C the collar which on its internal periphery is formed with an annular cylindrical flange D (Figs. 3 and 5) within which the cap B should make a tight fit. 50

It is when forcing the cap B into the annular flange D that the collar C is apt to be depressed or distorted with the result that the flange D may lose its cylindrical form and the cap B not make an air- and liquid-tight joint therewith. Therefore I strengthen the collar by spaced radial corrugations E E as shown in Figs. 1, 2, and 3, or by spaced spherical bulges F as shown in Figs. 4 and 5. These corrugations or bulges may be outward as shown or inward and formed at the same time as the collar is stamped or pressed so that no additional expense is involved beyond the preparation of a suitable die and mould. 60

What I claim and desire to secure by Letters Patent is:

A container of cylindrical form, comprising a body, a top of circular form secured to the upper edge of said body, and formed with a central circular aperture, said top being also formed with an annular channel between said aperture and the outer edge of the top, the bottom of said channel inclining upwardly towards the centre of the top of the container, said top having also a down turned flange constituting the wall of said aperture, and a dished cap fitted within said down turned flange and having a horizontal flange extending partly over said annular channel, the bottom of said channel being formed with radially disposed and upwardly pressed deformations extending under the flange of the cap to resist buckling of the top under pressure required to force the cap into the aperture. 75

Signed at Sydney, New South Wales this twenty-fourth day of December, A. D. 1923.

ROBERT OLIVER GEARY.
